UNITED STATES PATENT OFFICE.

ANDREW CHRISTIANSON, OF BUTLER, PENNSYLVANIA.

DRAFT GEAR.

Application filed April 16, 1925. Serial No. 23,849.

My invention relates to draft gear attachments such as are used in railroad cars and the like, and has for its object the provision of draft gear structure of such form that it 5 may be more conveniently assembled and disassembled for the purpose of making replacements and repairs than those structures heretofore employed.

Another object of my invention is to simplify and improve draft gear attachments 10 generally.

Some of the forms which my invention may take are shown in the accompanying drawings, wherein Fig. 1 is a partial plan 15 and partial sectional view of draft gear structure embodying my invention; Fig. 2 is a view taken on the line 2—2 of Fig. 1; Fig. 3 is a front elevational view of the structure of Fig. 1; Figs. 4, 5 and 6 are 20 views taken on the lines 4—4, 5—5, 6—6, respectively, of Fig. 1; Fig. 7 is a partial plan and partial sectional view of a modified form of draft gear structure; Fig. 8 is a side elevational sectional view thereof, and 25 Fig. 9 is a front elevational view of the structure of Fig. 8.

Referring now to Figs. 1 to 6, I provide draft sill structure having side plates 10 which may be of somewhat the usual form 30 and secured to the car body in any desired manner. Between the forward ends of the members 10 I mount a striking casting 11 which is of general rectangular form and is riveted to the side members 10, as shown 35 more clearly in Fig. 1. The forward vertical edges of the casting 11 are flanged outwardly at 12 and seat against the ends of the draft sill members 10. The casting 11, adjacent to its rear portion, is provided with 40 vertical ribs 13 and 14 at each side thereof and reinforcing flanges 15 and 16 to assist in receiving stresses imparted to locking pins 17 that extend through said flanges and between the ribs 13 and 14. The bottom 45 flanges are perforated for the reception of pins 18 upon which the lower ends of locking pins 17 rest.

A carry iron 20 is mounted within the forward end of the casting 11 and seats 50 against vertically disposed ribs 21 formed adjacent to the forward edge of the casting 11. The lower portion of the carry iron 20 is recessed as shown more clearly in Fig. 2. A bolt 22 lies within said recess and the 55 ends thereof extend through openings in the sides of the casting 11 and the draft

sill members 10, to detachably secure said carry iron 20 in position.

To the rear of the striking casting 11 a top plate 24 is riveted to the upper edges of 60 the plates 10, as shown more clearly in Figs. 2 and 6, and a bottom plate 25 is secured to the lower edges of the plates 10, to assist in enclosing the mechanism which will be hereinafter described.

A coupler shank 26 extends rearwardly 65 into the striking casting 11 and between the forward extremities of a yoke 27 which may be of the usual form. A pin 28 extends through the rear end of the coupler shank 70 and the legs of the yoke 27, to connect these members together in the usual manner.

A rear follower block 29 extends through 75 the yoke 27 and seats against angles 30 that are riveted to the rear ends of the members 10. A front follower block 31 is disposed between the legs of the yoke at their forward ends and seats against the rear sides of the pins or keys 17. The keys 17 are held in position as above explained, and 80 pulling strains imparted thereto through the coupler shank 26, yoke 27 and followers 29 and 31 are transmitted to the ribs 13 on the striking casting. The keys 17 and the ribs against which they seat provide extensive impact area for the pulling strains.

When the parts are assembled as shown 85 in Figs. 1 to 6, it will be seen that pulling strains are taken by the ribs 13 of the striking casting 11 and that buffing strains are 90 primarily imposed against the follower 29 and abutments 30, but at maximum compression of the draft gear spring, impact is also made against the forward edge of said casting and the carry iron 20. When it is desired 95 to remove the draft rigging, which consists of the yoke, follower blocks, a spring (not shown), and the coupler shank, the locking keys 17 may be lifted out, the bolt 22 removed, and the carry iron 20, which serves 100 as a vertical support for the coupler shank, removed. The coupler shank, yoke and follower plates may then be withdrawn 105 through the forward end of the striking casting. The removal of the carry iron 10 permits said parts to be lowered to pass the flanged striking portion 33 of the casting 11 (Fig. 2).

The arrangement above described avoids 110 the necessity of lifting the draft rigging mechanism into the draft sill from beneath the car, which is a difficult and tedious

operation, and permits repairs of the draft rigging to be conveniently made without placing the car in the shops. If the weight of the rigging is too great to permit the 5 workmen to manually replace it in the draft sill, the rear end of the yoke 27 may be moved into the striking casting a short distance and a locomotive then backed against the coupler to force the rigging rearwardly 10 into proper position, after which the keys 17 may be dropped into place and the carry iron 20 and the bolt 22 put in position.

Referring now to Figs. 7, 8 and 9, I show 15 a structure which is somewhat similar to that shown in Figs. 1 to 6, in that a yoke 27^a is mounted between draft sill members 10^a, and a striker casting 11^a, held in place by a locking pin 17^a, is provided. In this latter form of construction, however, it is 20 not necessary that the forward lower edge of the striking casting be inclined downwardly as is the casting 11 of Fig. 2, since instead of forming a striking flange 33 on the casting 11 as in Fig. 2, I provide, as 25 shown more clearly in Fig. 8, a striking member 33^a that is pivoted to the striking casting at 34. A carry iron 20^a is held in position by a bolt 22^a in somewhat the same manner as is the carry iron 20, and serves to 30 support the coupler shank 26^a and to assist in taking impacts imposed against the forward end of the structure.

The bolt 22^a, adjacent to its ends, rest in 35 slots 37 formed in the end of the sill member 11^a and open at their forward ends. The bolt is thus removable in a direction longitudinally of the draft sill. To normally hold the bolt 22^a in place, I provide washer-like members 36 that have oppositely 40 bent flanges at their front and rear edges, as shown in Fig. 7. Each rear flange engages a boss or lug on the draft sill member 11^a, to prevent accidental movement of the bolt from the slots, and the front flange 45 may serve as a nut lock, to prevent rotative movement of the bolt or the nut, as the case may be.

When it is desired to remove the coupler shank 26^a, the yoke 27^a, and associated parts, the key 17^a and the bolt 22^a are withdrawn and the coupler shank may then be pulled forwardly, either manually or by a locomotive or other car coupled thereto. During this movement the striking plate 33^a will 55 swing in a counter clockwise direction about its pivot 35, permitting the yoke and follower plates to pass, thereby rendering it unnecessary to flare the forward end of the casting 11^a.

60 I claim as my invention:

1. Draft gear structure comprising laterally spaced draft beam members, a hollow striking casting secured between the forward ends of said beam members, a yoke disposed 65 between said beam members, a follower plate

extending through said yoke, laterally spaced abutments on the interior of said casting, removable locking keys disposed between said abutments and said follower plate, and a removable coupler shank guide 70 on said striking casting.

2. Draft gear structure comprising laterally spaced draft beam members, a hollow striking casting secured between the forward ends of said beam members, a yoke 75 disposed between said beam members, a follower plate extending through said yoke, laterally spaced abutments on the interior of said casting, removable locking pins disposed between said abutments and said 80 follower plate, and a member removably mounted at the front of said casting and partially closing the open end thereof.

3. Draft gear structure comprising laterally spaced draft beam members, a hollow 85 striking casting secured between the forward ends of said beam members, a yoke disposed between said beam members, a follower plate extending through said yoke, laterally spaced abutments on the interior 90 of said castings, removable locking keys disposed between said abutments and said follower plate, and a member mounted at the front of said casting and partially closing the open end thereof, the said member 95 being positioned to afford vertical support to a coupler shank.

4. Draft gear structure comprising laterally spaced draft beam members, a hollow striking casting secured between the forward ends of said beam members, a yoke disposed between said beam members, a follower plate extending through said yoke, laterally spaced abutments on the interior of said casting, removable locking pins disposed between said abutments and said follower plate, and a member mounted at the front of said casting and partially closing the open end thereof, the said member being positioned to receive impacts against the 105 forward end of said casting.

5. Draft gear structure comprising side sill members laterally spaced for the reception of draft gear structure therebetween, and means for preventing withdrawal of a follower plate or the like in a direction longitudinally of said members, comprising vertically disposed stop members, keys seating against said stop members, and removable holding members adjacent to the lower edge 115 of the stop members, for supporting said keys against downward movement.

6. Draft gear apparatus comprising longitudinally recessed beam structure adapted to receive draft rigging, a vertically disposed stop member adjacent to the forward end of said beam structure, and a key releasably supported against withdrawal in a downward direction, the said key extending into said recess in position to engage the forward 125 130

surface of a portion of the draft rigging to prevent withdrawal thereof from the beam structure.

7. The combination with draft sill structure and draft rigging contained therein, of means for preventing withdrawal of the draft rigging in a longitudinal direction, comprising a key extending vertically

through said draft sill structure in position to engage the rigging, and means detachably connected to the lower side of said sill structure for limiting downward movement of the key.

In testimony whereof I, the said ANDREW CHRISTIANSON, have hereunto set my hand.

ANDREW CHRISTIANSON.
